Patented Aug. 11, 1959

185,834

COMBINED BRUSH HOLDER AND RECEPTACLE FOR CLEANSING LIQUID OR THE LIKE

James C. Lower, Toledo, and Phillip D. Sanborn, Chardon, Ohio, assignors to National Laboratories, Inc.,
Toledo, Ohio, a corporation of Ohio

Application May 7, 1958, Serial No. 50,788

Term of patent 14 years

(Cl. D9—2)

Fig. 1

Figure 1 is a front elevational view of the combined brush holder and receptacle cleaning liquid or the like, showing our new design the rear being substantially like the front shown;

We claim:

The ornamental design for a combined brush holder and receptacle for cleansing liquid or the like, as shown and described.
